UNITED STATES PATENT OFFICE.

BERTRAM MAHN, OF PHILADELPHIA, PENNSYLVANIA.

SMOKING-PIPE.

1,011,633.

Specification of Letters Patent. Patented Dec. 12, 1911.

Application filed April 13, 1911. Serial No. 620,736.

To all whom it may concern:

Be it known that I, BERTRAM MAHN, a citizen of the United States, residing at Philadelphia, in the county of Philadelphia and State of Pennsylvania, have invented certain new and useful Improvements in Smoking-Pipes, of which the following is a specification.

My invention relates to improvements in smoking pipes, the object of the invention being to provide an improved construction of pipe, in combination with an improved arrangement of tubular coil, which compels a long passage of the smoke before it reaches the smoker without lengthening the ordinary pipe, thus giving the smoker a cool smoke with the ordinary length of pipe.

A further object is to provide an improved coil, and improved means for connecting the coil with the pipe, whereby the smoke is compelled to take a long path from the bowl to the mouth piece, and which construction enables the removal of the coil, and the replacing of the same or a new coil whenever desired.

With these and other objects in view, the invention consists in certain novel features of construction and combinations and arrangements of parts, as will be more fully hereinafter described and pointed out in the claims.

In the accompanying drawings: Figure 1, is a view partly in longitudinal section and partly in elevation illustrating my improvements. Fig. 2, is a fragmentary view in plan showing the connection between the coil and the stem, and Fig. 3, is an enlarged perspective view of one of the split screws.

1, represents the bowl of a smoking pipe, 40 and 2 the stem portion integral therewith, and having a screw-threaded socket 3 in its free end to receive the ordinary mouth piece 4.

In the bottom of bowl 1, a pocket 5 is formed, and communicates with the main portion of the bowl by means of a restricted opening 6. The lower end of this pocket 5 is screw-threaded as shown at 7, for the reception of a sectional tubular thumb screw 8, and said pocket 5 is adapted to contain absorbent cotton 9, or other suitable material to withhold the nicotine in the smoke.

In the stem 2, adjacent mouth piece 4, a screw-threaded opening 10^a is provided for 55 a sectional tubular thumb screw 10, and said

opening 10^a communicates with a pocket 11, having a duct 12 which registers with the smoke duct 13 in mouth piece 4.

14, represents a pipe coil which may be made of any suitable material such as metal, hollow reed, or any tubular material which may be formed in a coil adapted to be positioned on stem 2. The respective ends of this coil 14, are provided with annular flanges 15 against which the ends of the tubular screws 10, bear, and when said screws are screwed into their respective openings, they will securely hold the coil in place. The ends of the coil, of course, must be suitably shaped as shown to allow a movement thereof in positioning the screws in pocket 5, and stem 2 respectively, and to also enable the removal of the screws so that the coil may be detached, cleaned and replaced, or a new coil substituted. By reason of this coil 14, the smoke from the bowl 1 will take a long cool trip through the coil, before it reaches the smoker, thus giving him a cool smoke with a relatively short pipe.

The absorbent cotton 9 in pocket 5 prevents the greater portion of nicotine from entering the coil 14, but in the course of events, it is probable this coil should be cleaned and replaced, and the coil may be readily removed by removing the sectional thumb screws 8 and 10.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A smoking pipe comprising a bowl, an integral stem thereon, and a mouth piece screwed into the stem, said bowl having a screw-threaded pocket in its base, said stem having a screw-threaded opening therein adjacent the mouth piece, said opening communicating with a duct through the mouth piece, a coil, and sectional externally screw-threaded tubular thumb screws positioned around said coil and screwed into the pocket and opening respectively, substantially as described.
2. A smoking pipe comprising a bowl, an

100

integral stem thereon, and a mouth piece 5 screwed into the stem, said bowl having a screw-threaded pocket in its base, said stem having a screw-threaded opening therein adjacent the mouth piece, said opening communicating with a duct through the mouth piece, a coil, sectional externally screw-threaded tubular thumb screws positioned around said coil and screwed into the pocket 10 and opening respectively, said coil having annular flanges at its ends positioned against the ends of said thumb screws, substantially as described.

3. A smoking pipe comprising a bowl, an 15 integral stem thereon, and a mouth piece screwed into the stem, said bowl having a screw-threaded pocket in its base, said stem having a screw-threaded opening therein adjacent the mouth piece, said opening communicating with a duct through the mouth piece, a coil, sectional externally screw-threaded tubular thumb screws positioned around said coil and screwed into the pocket 20 and opening respectively, said coil positioned about said stem, and said pocket 25 positioned about said stem, and said pocket

adapted to receive nicotin retaining material, substantially as described.

4. A smoking pipe comprising a bowl, an integral stem thereon, and a mouth piece 30 screwed into the stem, said bowl having a screw-threaded pocket in its base, said stem having a screw-threaded opening therein adjacent the mouth piece, said opening communicating with a duct through the mouth piece, a coil, sectional externally screw-threaded tubular thumb screws positioned around said coil and screwed into the pocket 35 and opening respectively, said coil having annular flanges at its ends positioned against the ends of said thumb screws, said coil positioned about said stem, and said pocket 40 adapted to receive nicotin retaining material, substantially as described.

In testimony whereof I have signed my name to this specification in the presence of 45 two subscribing witnesses.

BERTRAM MAHN.
